UNITED STATES PATENT OFFICE.

FRED E. NORTON, OF LYNN, MASSACHUSETTS, ASSIGNOR TO GENERAL ELECTRIC COMPANY, A CORPORATION OF NEW YORK.

ELASTIC-FLUID TURBINE.

1,091,011.

Specification of Letters Patent. Patented Mar. 24, 1914.

Application filed March 31, 1913. Serial No. 757,809.

To all whom it may concern:

Be it known that I, FRED E. NORTON, a citizen of the United States, residing at Lynn, county of Essex, State of Massachusetts, have invented certain new and useful Improvements in Elastic-Fluid Turbines, of which the following is a specification.

The present invention relates to multi-stage elastic fluid turbines, and has for its object to improve the construction and operation thereof, and also to improve the regulating mechanism therefor so that the same machine can be satisfactorily utilized as a high pressure condensing unit, as a high pressure non-condensing unit, and as an extraction machine supplying steam from some intermediate stage for heating, cooking, or other industrial purposes.

In certain of its aspects my invention may be considered as an improvement over that disclosed in my application for Letters Patent Serial No. 741,442, filed January 11, 1913.

For the consideration of what I believe to be novel and my invention, attention is directed to the accompanying description and claims appended thereto.

In the accompanying drawings which illustrate one of the embodiments of my invention, Figure 1 is a partial longitudinal section of a multi-stage turbine showing the parts arranged for non-condensing operation; Fig. 2 is a detailed view of the pressure regulating mechanism together with the means for changing over from condensing to non-condensing operation; Fig. 2^A is a detailed sectional view taken on a horizontal plane through the upper left hand portion of Fig. 2; Fig. 3 is a cross section of the turbine taken on line 3—3 of Fig. 1 looking toward the exhaust end and showing the parts in position for condensing operation; Fig. 4 is a partial sectional view showing the parts in position for non-condensing operation or for overload; Fig. 5 is a cross section looking toward the exhaust end of the machine showing the parts in position for non-condensing operation; Fig. 6 is a detailed view showing a means for yieldingly connecting the parts of the ring or stage valve, and Fig. 7 is a small plan view of the turbine.

Referring to Fig. 1, 8 indicates the casing of the turbine which is divided by diaphragms 9 and 10 into stages. In these 55 stages are located rotors or bucket wheels 11, 12 and 13. Each of these wheels may be provided with one or more rows of buckets 14. As shown each of the wheels is provided with two rows of buckets with more or less 60 complete rows of intermediate buckets 15 serving to change the direction of the motive fluid as it passes from one row of wheel buckets to the other. Motive fluid is admitted to the first wheel by the nozzles 16 65 and to the second wheel by the stage nozzles 17. The last wheel is provided with two sets of nozzles 18 and 19, the former receiving steam from the second stage subject to the control of a ring or stage valve to be described hereinafter, and the latter receiving 70 high pressure steam from the conduit 20 as indicated in Fig. 4. The admission of high pressure steam to the turbine is controlled by the valve 21 which also controls the passage of steam through the conduit 20 when 75 the turbine is operating non-condensing or when the turbine is operating under overload conditions. The wheels are mounted on the shaft 22 which is supported by suitable 80 bearings carried by the turbine casing or frame. Where the shaft passes through the diaphragms it is provided with packings 23 of any suitable construction. The ends of the shaft passing through the casing are also 85 packed in the ordinary manner. The casing is provided with two outlet chambers 24 and 25, the former being connected to the conduit 26 through which steam passes to the heating, cooking or other devices requiring relatively low pressure steam. The 90 chamber 25 is connected to a condenser of any suitable construction.

In order to operate a multi-stage impulse turbine in the most efficient manner it is 95 necessary to control the passage of steam through the low pressure nozzles of one or more of the stages. In order to avoid undue complication I have provided a valve for the last stage only. This same valve is also 100 utilized in controlling the pressure of the steam discharged through the chamber 24 to the extraction conduit 26. In carrying out this feature of the invention the inside

of the casing is provided with an annular wall 27 which is concentric with the axis of the shaft. This wall is provided with a plurality of radial ports as will appear 5 more fully hereinafter. Mounted for engagement with this annular wall is a ring-shaped stage valve 28. The valve is preferably made in two or more parts, each being provided with internal projections 29 as 10 shown in Figs. 3 and 5. These projections are united by bolts 30. Between the nut or head of the bolt and one of the projections 29 is a relatively stiff spring washer 31. The purpose of these washers is to permit the 15 valve as a whole to enlarge slightly thus making a good working fit with the interior of the annular wall or seat 27. This action of the valve parts is due to the fact that a higher pressure exists on the inside of the 20 valve than on the outside. I have shown the valve as being made in two parts, but under certain conditions it may be made in one piece with a slot on one side and a bolt 30 and a spring washer employed to unite 25 the adjacent ends of the valve. Referring to Fig. 3 the valve is provided with four sets of ports 35, 36, 37 and 38. The ports 35, 36 and 37 control the passage of steam from the second stage, which in the present 30 instance is the extraction stage, to the chambers 39, 40 and 41 supplying steam to the third stage nozzles 18. These chambers are formed between the annular wall 27 and the outer wall of the casing proper, there being 35 radial partitions 42 between the chambers so that each chamber can supply a group of nozzles or nozzle sections. The annular wall 27 is provided with a plurality of radial ports 43 which are controlled by the ring 40 valve. The relation of the ports in the valve to those in the wall 27 is such that by changing the angular position of the valve the amount of steam passing from the extraction stage to the third or low pressure 45 stage can be increased or decreased according to the conditions of operation. Viewed as an extraction machine the ring valve acts as an overflow valve to discharge to the chambers 39, 40 and 41 the steam which is 50 not required to maintain a constant pressure in the extraction chamber 24 and the conduit 26 connected therewith. Viewed from the aspect of a high pressure condensing unit the ring valve acts to put in serving 55 ice the proper number of third stage nozzles to convey the steam discharged from the second stage and at the same time maintain a constant pressure in said second stage. As before stated, the valve is also provided 60 with one or more ports 38 which register with ports 43 in the annular wall 27. Of the ports 38, the right hand one, when in the position shown in Fig. 3, controls the

passage of steam to one of the low pressure nozzles 18 from the second stage. When, 65 however, the valve is moved in a clockwise direction to its extreme position it controls the passage of exhaust steam from the chamber 25 into the chamber 24 as best shown in Fig. 1, this being the condition 70 when the turbine is operating on the non-condensing plan with the chamber 24 and conduit 26 connected to atmosphere, or in some cases to heating or cooking devices where suitable relief means are provided to 75 take care of any excess steam. It will thus be seen that the ports 38 function as exhaust ports, whereas the ports 35, 36 and 37 function as supply ports.

The ring valve is actuated by the following means:—Formed on the valve or attached thereto is the segment of a gear 45, Fig. 5, which meshes with a rack 46 carried by the rod 47 of the piston 48. The piston is mounted in a cylinder 49 and the 80 two form a motor. The motor is actuated by steam admitted by the pipe 50 subject to the control of the pilot valve 51. The exhaust from the motor escapes by the ports 52. The piston rod 47 is extended through 85 a packing in the turbine casing and on its end is provided with a block 53 which slides in the forked end of a lever 54, the latter being pivotally supported by a bracket 55. Pivotally attached to the lever 54 is a floating lever 56, the upper end of which is connected by a link 57 to a rod 58 attached to and moved by a sylphon diaphragm 59, Figs. 2 and 5. The diaphragm or equivalent device acts in opposition to the coiled extension spring 60, the tension of which can be adjusted by the hand wheel 61. Fluid under pressure from the second or extraction stage is admitted to the diaphragm 59 by the pipe 62 as shown in Fig. 5. The floating lever 56 is connected by a rod 63 with the pilot valve 51 controlling the motor. As the pressure in the extraction stage increases it causes the diaphragm to move the stage valve in a manner to increase the amount 100 of steam which passes to the third stage nozzles 18. Conversely as the pressure in the extraction stage decreases the diaphragm moves the pilot valve in a direction to cause the motor to shut off one or more nozzles 105 110 115 or groups of nozzles so that the pressure in the extraction stage will be kept constant. This action is the same whether the machine is working as an ordinary high pressure condensing unit or as an extraction 120 125 machine.

When a machine which is designed for condensing operation operates as a non-condensing unit a greater amount of steam is required for the same load. For this purpose the conduit 20, Fig. 4, and high pres-

sure nozzles 19 are provided which in effect convert the last wheel from a low to a high pressure wheel, the said nozzles 19 having the proper ratio of expansion between the throat and the discharge end to reduce the pressure of the steam to substantially that of the exhaust. Since the pressure of the steam in the second stage is substantially that of the atmosphere or exhaust pressure it is necessary in order to avoid loss incident to the ineffective use of steam to cut off a large part or all of the nozzle 18. To do this it is necessary to move the ring valve to the position shown in Fig. 5. This is accomplished in a simple manner by the means shown in Figs. 2 and 2^A. In the end of the link 57 is mounted a stud 64 which carries an eccentric 65. Keyed to the stud and the eccentric is a handle 66 which is normally held in either of its two positions by the spring pressed latch 67. This eccentric has the effect of changing the length of the link 57. Moving the handle to the position shown in Fig. 2^A increases its length and moving it to the opposite position 180° therefrom decreases its length. Assuming that the piston 48 of the motor is in some intermediate position and it is desired to shift the parts to non-condensing operation (the lower end of the floating lever 56 being fixed and also the right hand end of the link 57), turning the eccentric to the position shown has the effect of moving the pilot valve 51 to the left thus admitting steam from the conduit 50 to the left hand end of the cylinder and causing the piston to move to the right. As the piston starts into operation it moves the rod 47, block 53 and lever 54 and floating lever 56 to the right, thus restoring the pilot valve 51 to the neutral position which locks the piston 48 in the position shown. It will be noted that the rod 47, block 53, lever 54, lever 56, and rod 63 form a part of a follow-up device for restoring the pilot valve after a predetermined movement of the piston. This follow-up device is effective whether the movement of the piston be due to the action of the sylphon diaphragm 59 or the manual actuation of the eccentric 65.

Assuming the parts to be in the position shown in Figs. 1 and 5 for non-condensing operation, all of the steam which passes through the last wheel collects in the chamber 25 and passes upwardly through the ports 43 in the annular wall 27, thence through the valve ports 38 into the second stage and to chamber 24, from which it escapes through the pipe 26 to the atmosphere or to a heating or cooking device, if said pipe is connected therewith. Generally speaking when the turbine is operating as a non-condensing unit it will not be supplying

steam for heating purposes, though under certain conditions where suitable relief means are provided for excess steam it might do so. When the turbine is operating non-condensing, high pressure steam passes through the valve 21 to the first stage and also through the conduit 20 to the high pressure nozzles 19 of the third stage.

I have not illustrated in detail the construction of the valve 21 nor have I illustrated the speed governor for controlling it, since said valve mechanism and governor may be of any suitable or well known construction.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. The combination with a multi-stage turbine, of a supply valve, a valve for regulating the passage of fluid between stages, said valve having ports which are normally active in supplying fluid to a later stage and also a port that is normally inactive for conveying exhaust fluid from one of the rotors to a chamber, a motor for operating the valve, a means sensitive to pressure changes in one of the stages for normally controlling the motor, and means for rendering said pressure means inoperative and causing the motor to move the valve to a position where the exhaust port is active.

2. The combination with a multi-stage turbine, of a supply valve, a valve for regulating the passage of fluid between stages, said valve having ports which are normally active in supplying fluid to a later stage and also a port that is normally inactive for conveying exhaust fluid from one of the rotors to a chamber, a motor for operating the valve, a means sensitive to pressure changes in one of the stages, a controller for the motor that is connected to and actuated by said pressure responsive means, and means for modifying the connection between the pressure means and the controller for causing the motor to move the valve to the position where said exhaust port is open.

3. The combination with a multi-stage turbine, of a supply valve, a valve for regulating the passage of fluid between stages, said valve having ports which are normally active in supplying fluid to a later stage and also a port that is normally inactive for conveying exhaust fluid from one of the rotors to a chamber, a motor for operating the

4

valve, a means sensitive to pressure changes in one of the stages for normally controlling the motor, a floating lever that is moved by the motor and is attached to the pressure responsive means, and means interposed between the lever and pressure means for rendering the pressure sensitive means inactive and causing the motor to move the valve to one of its extreme positions.

10 4. The combination with a multi-stage turbine, of a supply valve, a valve for regulating the passage of motive fluid between stages, said valve having ports for supplying fluid from one stage to another and a normally inactive port for conveying exhaust from one of the stages when the turbine is operating non-condensing, a motor for operating the valve, a pilot valve for controlling the motor, a means movable in response to changes in stage pressure, a floating lever that is moved by the motor and is connected to the pressure sensitive means and to the pilot valve, and a two-position device that pivotally unites the lever and means and is so arranged that when in one of its positions said means controls the motor through the pilot valve and when in its other position the means is rendered inoperative and the pilot valve moved to a position to cause the motor to move to one of its extreme positions.

5 5. The combination with a multi-stage turbine, of a supply valve, a valve for regulating the passage of motive fluid between stages, said valve having ports for supplying fluid from one stage to another and a normally inactive port for conveying exhaust from one of the stages when the turbine is operating non-condensing, a motor for operating the valve, a pilot valve for controlling the motor, a means movable in response to changes in stage pressure, a floating lever that is moved by the motor and is connected to the pressure sensitive means and to the pilot valve, and an eccentric that pivotally unites the lever and means and which is so arranged that when turned it changes the relation between the pressure sensitive means and the pilot valve.

40 6. The combination with a multi-stage turbine having a cylindrical valve seat in one of the stages, a split ring valve that engages the seat and is capable of expanding slightly under fluid pressure, and yielding means that unite the opposed parts of the valve.

60 7. The combination with a multi-stage turbine having a cylindrical and ported valve seat, a ported ring valve that engages the seat and is divided into separate members, and yielding means that unite said ports and permit the valve to enlarge slightly in response to fluid pressure.

8. The combination with a multi-stage turbine having a cylindrical and ported valve seat, a ported ring valve that engages the seat and is divided into separate members, bolts for uniting the members of the valve, and spring washers for the bolts that permit the valve to enlarge slightly in response to fluid pressure.

9. The combination with a multi-stage turbine having a cylindrical and ported valve seat, a ported ring valve that engages the seat and is divided into separate members, yielding means that unite said ports and permit the valve to enlarge slightly in response to fluid pressure, a motor for actuating the valve, and gearing between the motor and valve, a part of which is attached to one of the valve members.

10. The combination with a multi-stage turbine arranged to operate condensing and non-condensing and having two fluid discharging outlets, one leading from the low pressure end of the machine, the other from a region of intermediate pressure, means for supplying high pressure motive fluid to the low pressure portion of the machine, and a valve for establishing communication between the rotor chamber of said low pressure portion and the said intermediate pressure region when the machine is operating non-condensing.

11. In combination, a turbine which is divided into stages, a rotor in each stage, a conduit connecting an intermediate and a low pressure stage, outlets communicating with intermediate and low pressure stages, and a valve controlling the conduit which is closed when the turbine is operating condensing and open when it is operating non-condensing.

12. In combination, a turbine which is divided into stages, a rotor in each stage, a conduit connecting an intermediate and a low pressure stage, outlets communicating with intermediate and low pressure stages, a valve controlling the conduit which is closed when the turbine is operating condensing and open when it is operating non-condensing, and means for supplying high pressure motive fluid to the low pressure stage.

13. In combination, a turbine which is divided into stages, rotors for the stages, a condensing outlet, a non-condensing outlet, a conduit connecting said outlets, a valve in the turbine which controls the supply of motive fluid from one stage to another and closes said conduit during condensing operation, means for moving the valve in a manner to open the conduit and also reduce the supply of fluid to the low pressure stage for non-condensing operation, means admitting motive fluid to the turbine, and

means for admitting high pressure fluid to the low pressure stage for non-condensing operation.

14. In combination, a turbine which is divided into stages, rotors for the stages, a valve for regulating the pressure in one of the stages which has supply and exhaust controlling ports, means for moving the valve in a manner to put the supply or ex-

haust ports into service, a condensing outlet, a non-condensing outlet, and means for supplying motive fluid to the turbine.

It witness whereof, I have hereunto set my hand this 26 day of March 1913.

FRED E. NORTON.
